UNITED STATES PATENT OFFICE.

SAMUEL P. LANGMAID AND LEONARD A. WALTON, OF SEATTLE, WASHINGTON.

SPARK-TROUBLE LOCATOR.

1,376,022.

Specification of Letters Patent. Patented Apr. 26, 1921.

Application filed September 1, 1920. Serial No. 407,454.

To all whom it may concern:

Be it known that we, SAMUEL P. LANGMAID and LEONARD A. WALTON, subjects of the King of Great Britain, residing at Seattle, 5 in the county of King and State of Washington, have invented certain new and useful Improvements in Spark-Trouble Locators, of which the following is a specification.

10 This invention relates to an improvement in indicators designed to be secured to the dash of automobiles and the like, to provide visual indication at all times of the operating condition of the spark plugs of the engine.

15 The improved indicator comprises a member having contacts arranged to provide a gap in the circuit conductor from the coil or coils, or the distributor to the spark plugs, so that there is visual indication of the 20 sparking action of each particular plug. The indicator also includes a ground wire having a slightly greater gap break with each of the leading-in wires of the indicator, 25 so that in the event of an interruption of the current to the spark plugs, or a break in the plug, the current, through the indicator, will jump the gap to the ground wire, and thereby indicate the failure of operation of 30 the particular spark plug.

In the drawings:

Figure 1 is a plan of the improved indicator.

Fig. 2 is a vertical central section of the 35 same.

Fig. 3 is a broken elevation showing the indicator in place on the vehicle dash.

The improved indicator comprises what 40 may be termed a base 1, of insulating material, the base being preferably circular in plan and having an annular edge rib 2 on the upper surface. A ground contact post 3 is passed centrally through the base, having an appropriate contact head 4 on its upper 45 end, resting squarely on the base. The post 3 is secured in place by nuts 5 seated in a recess 6 in the under surface of the base, these nuts also serving as a means for connecting a ground wire 7 to said ground post 50 3. A series of contact posts 8, one for each cylinder of the engine is arranged in an annular row, concentric with the ground post 3, and spaced equal distances apart. These posts 8, which will be hereinafter 55 termed leading-in posts, are connected respectively by wires 9, to the particular coils,

or to the contact points in the usual distributor head, according to which type of current distribution is used in the particular machine. The posts 8 have contact heads 11 60 of appropriate form resting upon the upper surface of the base, and are held in place by nuts 10, seating in recesses 12 in the lower surface of the base, these nuts also serving to secure the wires 9 to the posts 8. 65

Surrounding and concentric with the posts 8, are a second series of posts 13, secured in place by nuts 14 seating in recesses 15 in the lower surface of the base, these posts 13 serving as contact posts for, and being connected to the respective spark plugs by conductors 16, secured by the nuts 14. These posts 13 hereinafter termed the leading-out posts, are arranged in an annular series beyond the posts 8, and preferably in radial 75 alignment respectively with the posts 8.

The upper end of the ground post 3 is provided with a star-shaped contact member 17, having a point 18, extended toward and providing a suitable air gap with the upper 80 end of the adjacent post 8. Similar star-shaped contacts 19 are provided on the upper end of each of the leading-out posts 13, but these contacts 19, which may have any number of points desired, are mounted 85 eccentrically on the posts 13, so that one or other of the points may be given any desired air gap disposition with the adjacent post 8.

Assuming the parts arranged and connected as described, the indicator, which is secured at a convenient place on the dash or instrument board of the vehicle will indicate the condition of operation of the respective spark plugs. So long as the particular spark plug circuit is intact, the passage of the current thereover will be indicated by the spark between the particular contact 19 of the leading-out post and the head of the particular leading-in post 8. If 90 for any reason the spark plug becomes broken, the points unduly separated, or the circuit thereto broken, the leading-in current of the post 8 corresponding to that particular plug will follow the next shortest path 95 of exit, that is, to the point of the star-shaped contact 17 of the ground post 3. This spark of course is visible and will not only indicate trouble in the particular spark plug circuit, but will of course specifically 100 indicate the spark plug involved. The star contacts 19 of the leading-out posts provide 105 110

an additional gap in the spark plug circuit with the well known effect of intensifying the current between the spark plug points. Of course it is understood that the gap between the leading-in posts and the ground post is at all times greater than the gap between the leading-out posts and the leading-in posts.

If desired and as preferred, the indicator is protected without interfering with its visibility by providing a glass plate 21, to overlie the upper surface of the base, and rest upon the rib 2, a cap 22 having a central opening 23 being threaded to the base at 24, and securing the glass cover in place. By this arrangement the sparking terminals of the indicator are protected, and yet readily accessible when desired for adjustment or repair.

Claim:

An indicator for spark plug circuits including an insulating base, a ground post arranged therein, a series of leading-in circuit posts arranged in concentric relation with the ground post, a series of leading-out circuit posts arranged in concentric relation with the leading-in posts, a spark-gap member having a plurality of points mounted eccentrically on the upper end of each leading-out post to permit variation in the gap between said post and the particular leading-in post, and a plural point spark-gap member carried by the upper end of the ground post.

In testimony whereof we affix our signatures.

SAMUEL P. LANGMAID.
LEONARD A. WALTON.
